Primary Examiner — Samantha Wood(74) *Attorney, Agent, or Firm* — Muncy, Geissler, Olds & Lowe, P.C.(57) **CLAIM**

The ornamental design for a faucet, as shown and described.

DESCRIPTION

FIG. 1 is a front perspective view of a faucet according to the present invention.

FIG. 2 is a front view of the faucet of FIG. 1.

FIG. 3 is a rear view of the faucet of FIG. 1.

FIG. 4 is a left side view of the faucet of FIG. 1.

FIG. 5 is a right side view of the faucet of FIG. 1.

FIG. 6 is a top view of the faucet of FIG. 1; and,

FIG. 7 is a bottom view of the faucet of FIG. 1.

The broken lines are included for the purpose of illustrating the environmental structure and form no part of the claimed design.

The faucet is shown with symbolic breaks in length. The appearance of any portion of the article between the break lines forms no part of the claimed design.

1 Claim, 7 Drawing Sheets(56)
